United States Patent Office

Des. 218,019
Patented July 14, 1970

218,019

BOTTLE

Marcel Lattraye, Vittel, Vosges, France

Filed Apr. 23, 1969, Ser. No. 16,856

Term of patent 14 years

Int. Cl. D9—01

U.S. Cl. D9—73

FIG. 1 is an elevational view of a bottle showing my new design;

FIG. 2 is an elevational view with the bottle rotated 135 degrees in a clockwise direction; and

FIG. 3 is a top plan view thereof.

I claim:

The ornamental design for a bottle, as shown.
